TRACK-ALIGNING DEVICE

David Eich, Ashland, Wis.

Application July 27, 1945, Serial No. 607,419

1 Claim. (Cl. 254—44)

1

This invention relates to a railway-track aligning device, and more especially to refinements over the device disclosed in a prior Letters Patent No. 2,188,818, issued on the 30th day of January 1940.

The primary object of the invention is the provision of a railway track aligning device wherein the spanning bar is constructed with runner flanges which operate in grooves formed in the standard or shank into which the said bar is telescopically interfitted and in this manner the spanning bar is supported for free and smooth sliding action without frictional contact between the ratchet teeth of the spanning bar and the adjacent surfaces of the shank, the said spanning bar being manually operated by a ratchet medium operatively engaged with the ratchet teeth.

Another object of the invention is the provision of a device of this character, wherein it involves many refinements over the subject matter of Letters Patent No. 2,188,818, issued on the 30th day of January 1940. The said device in its application to a track gives a better view thereto for the man who sights the rail as he must stand about one hundred and fifty feet (150) or so away from the man who operates the said device, and the latter does not lie over the rail and thus obstruct the view of such rail.

A further object of the invention is the provision of a liner of this character, wherein the assembly of its parts is novel and unique, it enabling greater leverage, and is possessed of maximum moving power, without liability of displacement when in a set working position.

A still further object of the invention is the provision of a liner of this character, which is simple in construction, thoroughly reliable and efficient in operation, strong, durable, readily and easily operated, conveniently anchored in a set working position, giving full view to the rail, possessed of few parts, these being fully accessible, and inexpensive to manufacture and install.

With these and other objects in view the invention consists in the features of construction, combination and arrangement of parts as will be hereinafter more fully described, illustrated in the accompanying drawing, which discloses the preferred embodiment of the invention, and pointed out in the claim hereunto appended.

In the accompanying drawing:

Figure 1 is a side view of the track liner constructed in accordance with the invention and in an applied position to the work.

Figure 2 is a vertical longitudinal sectional view

2

through the track liner and taken on the line 2—2 of Figure 3.

Figure 3 is a transverse sectional view taken on the line 3—3 of Figure 2 looking in the direction of the arrows.

Figure 4 is a transverse vertical sectional view taken on the line 4—4 of Figure 1.

Similar reference characters indicate corresponding parts throughout the several views in the drawing.

Referring to the drawing in detail, A designates generally the liner or device constructed in accordance with the invention and in its entirety, while B denotes the rail of a track to be operated upon thereby for the alining of the track when required.

The liner or device A comprises a main body framework, having an elongated tubiform standard or shank 10, which may be built sectional or unitary, and is of substantially square formation in cross section throughout its length.

The standard or shank 10 has formed at one end an outturned external marginal web 11, which is seated in a countersunk or seat 12, in the outwardly bowed inner face of an abutting head or jaw 13, constituting the base plate of the framework, as well as an anchoring piece for the liner or device. This head or jaw 13 at the top or uppermost edge is formed with an outturned lip 14 which projects at substantially right angles thereto to function as a driving ledge, while the lowermost or bottom edge of this head or jaw creates a blunt knife blade 15, or a spiking medium, the confronting faces of the web 11 and the head or jaw 13 being correspondingly shaped to each other at the counterseat 12, where the said web 11 is joined with the jaw by fasteners 16.

The standard or shank 10 interiorly thereof forms a longitudinal way for the slidable interfitting therein of a spanning bar 17, which at opposite side edges, next to its top face with lateral runner flanges 18, slidably interfitting guide grooves or channels 19 formed in opposite side walls of the standard or shank. On the upper face of the spanning bar 17 in a longitudinal direction thereof and medially with relation to the runner flanges 18, are ratchet or rack teeth 20 disposed in a row. The runner flanges 18 are arranged to prevent the teeth 20 from making contact with an inner surface next thereto of the standard or shank 10, and in this manner preventing rubbing or retarding action therebetween, so that the bar will have free smooth sliding movement within such standard or shank 10 in the working of the liner or device.

The uppermost side or top face of the standard or shank 10 is formed with an elongated window or slot 21 in register with the row of teeth 20, and rising from this side or top face, medially thereof, and at opposite sides of the window or slot 21 is a double ear bearing 22, in which is horizontally pivoted at 23 for vertical rocking movements a lever 24, which is provided with a forked end 25 having pivoted therein at 26 a ratchet dog or pawl 27 for ratchet engagement with the teeth 20, so that the bar works outwardly from the standard or shank, as should be apparent, in a step-by-step manner. The dog or pawl 27 is formed with a laterally extended releasing hand-hold for the manual moving of the dog or pawl in releasing engagement thereof with the teeth. The other end of the lever 24 is socketed for the securing of a handle 29 thereto, so that the liner or device A can be operated manually, which is used for aligning track rails, the usable position being shown in Figure 1 of the drawing.

The outer end of the spanning bar 17 is provided with a fork 30 in which is pivoted at 31 a rail ball engaging hook 32, which is formed with a contact jaw 33 and underslung hook jaw 34, respectively, this being the same as disclosed in Letters Patent No. 2,188,818, and appears in Figure 2 of the drawing herewith. The shoe member denoted at 13 includes a base plate having an angular flange adapted to engage securely the ballast between the ties when aligning a rail B. The dog or pawl 27 plays through the window or slot 21 in the framework of the liner or device A.

What is claimed is:

A railroad track-aligning device comprising a tubiform shank composed of upper and lower sections detachably connected together, the lower

section being substantially U-shape in cross section, said upper and lower sections at their meeting edges being extended outwardly to form opposed longitudinal grooves, a base plate secured to and closing one end of said shank, a spanning bar slidably mounted in the lower section of said shank having longitudinal runner flanges on opposite sides adjacent its upper face adapted to slidably interfit in the grooves of the shank, ratchet teeth on the upper face of said spanning bar, a rail engaging hook pivotally connected to the outer end of said spanning bar, a double lug bearing formed integral with the upper section of the shank adjacent the base plate, a lever pivotally mounted adjacent its lower end in said bearing, a pawl pivotally connected to the lower free end of said lever adapted to move in a longitudinal slot in the upper section of said shank and operatively engage said ratchet teeth to move said spanning bar longitudinally of the shank and a web bridging the lugs of said bearing in the path of movement of the lower free end of said lever to limit the forward movement of said lever and backward movement of said pawl.
